UNITED STATES PATENT OFFICE

CARL H. HOFFSTETTER AND ROBERT F. HOFFSTETTER, OF ERIE, PENNSYLVANIA

DESIGN FOR A STOVE OR RANGE

Application filed August 4, 1932. Serial No. 44,527. Term of patent 14 years.

To all whom it may concern:

Be it known that we, CARL H. HOFFSTETTER and ROBERT F. HOFFSTETTER, citizens of the United States, residing at Erie, in the county of Erie and State of Pennsylvania, have invented a new, original, and ornamental Design for a Stove or Range, of which the following is a specification, reference being had to the accompanying drawing, forming part thereof, and in which drawing the figure is a

perspective view of a stove showing our design, the stippled effect shown representing a finish which covers a substantial portion of the stove.

We claim:

The ornamental design for a stove or range, as shown and described.

CARL H. HOFFSTETTER.
ROBERT F. HOFFSTETTER.
